UNITED STATES PATENT OFFICE.

SUTHERN KALFUS, OF LOUISVILLE, KENTUCKY.

COMBINED COOLER AND FILTER.

SPECIFICATION forming part of Letters Patent No. 274,339, dated March 20, 1883.

Application filed August 19, 1882. (No model.)

To all whom it may concern:

Be it known that I, SUTHERN KALFUS, of Louisville, in the county of Jefferson and State of Kentucky, have invented certain new and useful Improvements in a Combined Cooler and Filter; and I do hereby declare that the following is a full, clear, and exact description of the invention, which will enable others skilled in the art to which it appertains to make and use the same, reference being had to the accompanying drawings, and to the letters of reference marked thereon, which form part of this specification.

Heretofore water-coolers with filters have been constructed with a water-drip around the outside, as well as disks for filtering purposes, in connection with filtering material, such being capable only for imperfectly cooling and filtering the water. The disadvantages arising from the arrangement of the above devices are such that it is impracticable to cool and filter the water thoroughly without the use of felt or other fibrous material around the exterior of the cooler, as it is upon this fibrous material the water is drawn up constantly by capillary attraction from the saucer that holds the vessel, and as it is well known that in the tropical States, where the climate is hot, the water is brackish and very impure, and that it requires a filter and cooler that will more thoroughly cool and filter the water than has hitherto been done, and to also produce a vessel or jar for preserving and keeping cool meats, vegetables, &c., as well as to protect the contents of the jar from insects, which are very numerous in that and other sections of the country; and to this end my invention consists in the novel construction and arrangement of parts, whereby these defects are overcome and the water cooled and filtered thoroughly without the use of ice.

The annexed sheet of drawings, to which reference is made, fully illustrates my invention, in which—

Figure 1 represents a vertical sectional view of my improved cooler and filter. Fig. 2 is a horizontal sectional view taken through the cover. Fig. 3 is also a horizontal sectional view taken through the body of the cooler, showing a plan view of disk. Fig. 4 is a similar view to Fig. 3, showing bearings and indentations. Fig. 5 is a sectional view in modi-

fied form, and containing family jar or vessel. Fig. 6 is a horizontal section of Fig. 5, showing bottom bearings to support inside vessel. 55

Referring by letters to the accompanying drawings, A designates a vessel that forms the body of the cooler, having on its inner side lugs a, and at or near the bottom an opening, in which is placed a suitable faucet, a', and around the exterior of said vessel is wrapped felt or any suitable porous or fibrous material, for a purpose hereinafter mentioned.

B B indicate perforated disks, placed one above the other and within the vessel, which are supported in position by lugs a.

C indicates a tube open at both ends, and extending from the lower disk to near the top of the vessel, for exhausting air from the lower chamber or compartment from which the water is drawn.

The positions of the disks are such that the vessel is divided into chambers or compartments, in the present instance three, b b' b'', the upper one, b, containing filtering material—such as sand, gravel, &c.—and the middle one, b', also containing charcoal or other good filtering material, while the lower chamber, b'', contains the filtered water. The inside of this water-compartment b'' is glazed. 80

D designates the lid or cover, made hollow, forming a chamber, c, and provided with a hand-knob, c', having an opening, c'', forming a passage that communicates with said chamber c in the lid, and the same is further provided with small perforations d in its bottom, near the edges thereof, and just outside of the wall of the vessel, inclined so as to jet water against fibrous covering. This lid or cover is glazed on its bottom, and has an annulus thereon, as shown in Fig. 1. 85

E represents a saucer or pan, in the bottom of which is placed a mat, d', of flexible material, and upon which the cooler rests when placed within the saucer. 95

Having described the different parts of which my cooler is constructed, I will now explain the operation.

The lid or cover is removed and the water is poured into the vessel. The water then passes down through the sand and upper disk, through the perforations to the next chamber, thence through the charcoal and through the perforated disk B, and finally enters the lower

chamber, b^2 , the water being filtered or purified on its passage through the same. The water lid or cover is then filled with water through the opening c^2 , and through the small perforations in the bottom thereof the water dribbles upon and saturates the felt on outside cover of the vessel, which keeps the felt moist as fast as the water evaporates, and keeps the water in the vessel cool, the water dribbling over the fibrous material being received in the saucer.

Fig. 5 shows the vessel or jar slightly modified in form, the same to be used for preserving and keeping cool meats, vegetables, &c., (in this instance the filtering material is dispensed with,) and has the lugs and wrapping, as shown in Fig. 1, and the outside vessel may be constructed of stone, earthenware, or any suitable material, and is to be placed within a saucer and have a cover similar to the one above described.

In the bottom of the vessel as modified I construct projections or ribs e , on which rests a smaller vessel, e' , constructed of metal—such as tin, zinc, &c.—with shelves or half-perforated disks made of beech, maple, or cedar wood; or they may be made of metal, as may be found most convenient or practicable, forming compartments, as shown in dotted lines, and having a suitable cover and reversible handles secured to the vessel.

It will be observed that in placing the one vessel within the other the disks B B are removed. The water dribbling from the cover on the outer vessel keeps the inner vessel cool, while the projections in the bottom elevate the inner vessel and permit air to circulate around said vessel; also, it will be observed that the disks can be easily removed, when desired, by simply registering the openings e^2 with the lugs of the vessel A . The mat in the saucer protects the latter and the vessel from injury when the vessel is carelessly seated within said saucer.

Having thus described my invention, what I claim as new, and desire to secure by Letters Patent, is—

1. The combination of the water cooler and filter and drip pan or saucer, provided with a

mat for the reception of the water that dribbles from the cover, and for feeding or supplying water from said pan to the felt covering of the vessel, which is in contact with the vessel and water, all substantially as set forth. 50

2. In a water cooler and filter, the cover, constructed as described, provided with inclined perforations, each inclined toward the wall of the vessel or cooler, the vessel being provided on its exterior with a covering of fibrous material, and the cover with an annulus on its under side for keeping the cover in position, substantially as described. 55

3. In a water cooler and filter, the combination, with the vessel provided with lugs and removable disks, said vessel being also provided with upwardly-projecting ribs and adapted 60 to receive an inner vessel when the disks are removed, substantially as described.

4. A filtering-vessel for water and for conserving food, constructed with inner projecting lugs for the support of disks when used, and when removed for centering an inclosing-vessel, the filtering-vessel being glazed to the height of the lower water-chamber, said vessel being adapted to be wrapped with fibrous material, and provided with a water-chambered lid or 70 cover, which is also adapted to continuously moisten the wrapping, in combination with an outside water-receptacle, substantially as described. 75

5. A filtering and cooling vessel provided 80 with disks or diaphragms, said disks having pieces cut out of their edges to permit passage over supporting-lugs, and to register with said lugs when withdrawn, the lugs being arranged to support the disks in position by 85 slightly turning the disks, in combination with a central air-tube which forms a handle for raising the disks out of the vessel, as described.

In testimony that I claim the foregoing as my own I affix my signature in presence of two 90 witnesses.

SUTHERN KALFUS.
